(57) **CLAIM**

The ornamental design for a table circular saw, as shown and described.

DESCRIPTION

FIG. 1 is a rear, right, upper perspective view of a table circular saw showing our new design;

FIG. 2 is a front, left, upper perspective view thereof;

FIG. 3 is a front view thereof;

FIG. 4 is a rear side view thereof;

FIG. 5 is a left side view thereof;

FIG. 6 is a right side view thereof;

FIG. 7 is a top plan view thereof; and,

FIG. 8 is a bottom view thereof.

The broken lines represent the unclaimed portions of the table circular saw and form no part of the claimed design.
